UNITED STATES PATENT OFFICE.

WILBUR F. OSBORNE, OF ANSONIA, CONNECTICUT.

DESIGN FOR A SUSPENDER-END.

SPECIFICATION forming part of Design No. 17,362, dated May 31, 1887.

Application filed May 5, 1887. Serial No. 237,278. Term of patent 3½ years.

To all whom it may concern:

Be it known that I, WILBUR F. OSBORNE, a citizen of the United States, residing at Ansonia, in the county of New Haven and State of Connecticut, have invented and produced a new and original Design for Suspender-Ends, of which the following is a specification.

The object of this design is to provide a novel fancy suspender-end; and it consists in 10 a suspender-end having the longitudinal edges of one face of a color contrasting with the color of the longitudinal edges of the opposite face, and the longitudinal central body of the opposite faces of colors contrasting, respectively, 15 with the colors of said edges.

The design is illustrated by the accompanying drawings, in which Figure 1 is a plan view of a suspender end, showing one face thereof. Fig. 2 is a similar view showing the opposite 20 face.

In the drawings, the numeral 1 indicates the longitudinal central body of the suspender-end, and 2 the longitudinal edges thereof.

These edges in one face, Fig. 1, are of a color contrasting with the color of the edges on the 25 opposite face, Fig. 2. The color of the longitudinal center on each face of the braid is of a color contrasting with the color of the edges on that face of the braid, as is represented by Figs. 1 and 2.

Having thus described my invention, what I claim is—

The design for a suspender-end having the opposite edges of one face of a color contrasting with the color of the opposite edges 35 of the other face, and the central body of the faces of colors contrasting, respectively, with the colors of the said edges, substantially as shown and described.

In testimony whereof I affix my signature in presence of two witnesses.

WILBUR F. OSBORNE.
